COMBINATION HOLDER AND VACUUM-TIGHT SEAL FOR ENVELOPES

Henry H. Schmalz, Des Plaines, Ill., assignor to
The Rauland Corporation, Chicago, Ill., a corporation of Illinois

Application March 9, 1948, Serial No. 13,886

1 Claim. (Cl. 226—20.4)

1 This invention relates to an improved means for holding envelopes which may be made out of glass, metal, plastics, etc., e. g., bottles for cathode ray tubes, while evacuating the envelope. Heretofore a vacuum seal between an evacuating system and envelope was made either around the outside surfaces of the envelope's neck at its open end or around its inside surfaces. Commonly a stopper or expansion rubber attachment was employed to make the seal.

Some of the obvious disadvantages of such a device was that to establish a vacuum tight seal a tight fit had to be made between the stopper, the side wall of the envelope and the evacuating system. In making such a fit often, in spite of all precautions, breakage at the neck portions of the envelope resulted. Since the seal contacted the envelope at its weakest end and over only relatively small surface portions, separate supporting means for the envelope also had to be provided.

These and other disadvantages are overcome by my envelope support which enables anyone, skilled or unskilled, simply by placing an envelope in my holder to establish a vacuum tight seal between the envelope and a vacuum system.

According to my invention, the holder is provided with a resilient member which forms the point of contact between the holder and an envelope placed therein. At another point, the holder is connected to an evacuating system which evacuates the envelope through the opening in its neck. The resilient member acts as a self-sealing device, permitting evacuation of the envelope without having to connect it directly to the evacuating system. In this way, I am able to make full utilization of the speed of the evacuating system and an envelope may be evacuated as rapidly as the opening in its neck will permit. Heretofore, a small perforation was provided in the stopper which served as the connection between envelope and the evacuating system, thus it was not possible to remove the air from the tube any faster than it could be drawn through the small connecting hole.

I have found my holder to be particularly useful during an interim stage of manufacturing a cathode ray tube to produce a processing vacuum quickly and easily so that certain operations, such as aluminizing the interior of the tube, or checking the fluorescent screen by the gas ionization method, may be carried out.

My device is of simple yet rugged construction and will accommodate envelopes of varying sizes and contours without any adjustment of the

holder. The loading of the device is a simple operation capable of being carried out at high speed, and lends itself more readily to mass production techniques than any of those previously known.

The invention will now be described in greater detail with reference to one embodiment thereof shown in the single figure in which the bottle of a cathode ray tube mounted in a holder, partly in side elevation and partly in cross section, is illustrated.

1 is a cathode ray tube envelope or bottle standing on its long axis with face **2** of the bottle up. Bottle **1** is supported by a holder generally indicated at **3**, consisting principally of a cylinder **4** of a metal, such as brass, suitable for use in an evacuating system.

The top end of cylinder **4** has a collar **5** surrounding it and to the inside of which a washer **6** of resilient material, such as rubber, is cemented or otherwise suitably fastened to make a vacuum tight seal between the washer and collar. Cylinder **4** is of sufficient diameter and length to accommodate all of neck **7** of bottle **1**. The diameter of collar **5** is large enough so that part of the flared or conical portion **8** of bottle **1** penetrates into it. The extent of penetration may vary within wide ranges, but enough of the conical portion **8** should be engaged to provide a suitable support for the whole bottle. The glass wall of **8** rests directly against resilient washer **6**.

The bottom end of cylinder **4** is provided with a suitable connection, such as flange **9**, for attaching holder **3** to an evacuating system (not shown) which evacuates bottle **1** through open end **10** of neck **7**. A vacuum tight braze **11** is provided between cylinder **4**, collar **5** and flange **9**.

The weight of bottle **1** on washer **6** is sufficient to provide a seal at the point of contact with the washer. Furthermore, as suction is applied by the evacuating system, a combination of atmospheric pressure on the outside of the bottle and the weight of the bottle cause conical portion **8** to be pressed more tightly against washer **6**, whereby a self-seal is established which improves as the evacuation continues.

I have found that a more perfect seal between the holder and bottle may be obtained when the surface of washer **6** contacting portion **8** is a relatively narrow one such as that afforded by point contact. As illustrated in the drawing, one way of doing this is to give a square cross section to washer **6** so that only corner **12** of the washer contacts the bottle. However, it is enough if the resilient washer offers little resistance to the

weight of the bottle at the point of initial contact so that at least a portion of the washer will be easily compressed and the self-sealing characteristics enhanced. The seal may be improved by applying vacuum grease, oil or the like to the portions of the washer contacting the bottle. Heretofore, the use of such lubricants often resulted in contamination of the inside surfaces of the bottle because, the seal being close to the open end of the neck, the lubricants got inside the bottle. This cannot happen with my structure because the seal is at a point remote from the neck opening.

A plurality of holders 3 may be connected to a single vacuum system or to a continuous rotary 15 or line type vacuum system and when it is desired to evacuate bottles, a vacuum tight seal between each bottle and the system is established simply by dropping a bottle into a holder.

It will be obvious to those skilled in the art 20 that various changes and modifications may be made in the structure here disclosed without departing from the spirit and scope of my invention.

What is claimed is:
In a combination holder and vacuum tight

5 seal for the bottle of a cathode ray tube having an open-ended neck and conically shaped side walls, a cylinder for supporting the bottle, a collar fastened adjacent the upper end of said cylinder, a resilient washer having a square cross section cemented vacuum tight to the inside surface of said collar, the entire bottom and at least one side of said washer being supported by said collar, said resilient washer having a sharp edge 10 diagonally opposite the bottom outer corner thereof for contacting said conically shaped side walls of said bottle to form a vacuum tight seal therewith, and means for fastening the bottom end of said cylinder to a vacuum system.

HENRY H. SCHMALZ.
